UNITED STATES PATENT OFFICE

154,227

DESIGN FOR A NAIL FILE

Jose Manuel Alvizua, New York, N. Y.

Application May 22, 1948, Serial No. 146,521

Term of patent 7 years

(Cl. D86—10)

To all whom it may concern:

Be it known that I, Jose Manuel Alvizua, a citizen of the United States, residing at New York, in the county of New York, in the State of New York, have invented a new, original, and ornamental Design for a Nail File, of which the following is a specification, reference being had to the accompanying drawing, forming a part hereof.

Fig 1 is a side elevational view of a nail file, showing my new design; Fig. 2 is a top plan view; Fig. 3 is a bottom plan view; and Fig. 4 is a perspective view.

I claim:

The ornamental design for a nail file, as shown.
JOSE MANUEL ALVIZUA.
